UNITED STATES PATENT OFFICE

CLARENCE A. SMITH, 2D, OF WETTOWN, PENNSYLVANIA, ASSIGNOR OF ONE-HALF TO
GABRIEL MASSENA, OF PHILADELPHIA, PENNSYLVANIA, AND ALFRED V. DU PONT,
OF WILMINGTON, DELAWARE

PENCIL POINTER

Application filed May 27, 1932. Serial No. 614,023.

This invention relates to pencil pointers and more particularly to pencil pointers of the kind comprising a plurality of superposed connected abrasive sheets.

Devices of the general character referred to are well known and are used extensively by engineers, artists, designers, architects, and others engaged in similar work. The conventional device of this kind comprises a

plurality of superposed sheets mounted on a wooden paddle and being joined together by means of glue applied along their outer edges. These prior devices have been found to be not entirely satisfactory, principally be-

cause of the marked tendency of the sheets to become detached accidentally before they have been used up entirely and also due to the soiling of the hands occasioned by removing a used sheet. It is common practice for draftsmen and other users of these devices to suspend them from a drawing board on a string, the device thereby being subject to being bumped frequently, resulting in the abrasive sheets' being separated from each other or the paddle accidentally.

An object of this invention is to provide an improved device of the character described in which the abrasive sheets are connected to each other and to the paddle or base in such a way as to insure against accidental removal of the sheets.

Another object is to provide an improved construction of the kind specified including means for facilitating intentional removal of individual sheets without soiling of the user's hands.

Figure 1 is a perspective view of a pencil sharpener embodying the invention in a preferred form;

Figure 2 is a central, vertical, sectional view of the device shown in Figure 1;

Figure 3 is a sectional view taken on the line 3—3 of Figure 2;

Figure 4 is a top plan view of a modification; and

Figure 5 is a fragmentary vertical sectional view of the device shown in Figure 4.

Referring to Figures 1, 2, and 3 of the drawing, which illustrate a practical and preferred embodiment of the invention, there is shown a pencil sharpener device comprising a base A and a pad B mounted on the base, the pad including a plurality of super-

posed sheets 1. The central portion of the top face of each of the sheets 1 is provided with abrasive material 2 adapted to be used for sharpening the pencil graphite in the well known manner, and in accordance with the present invention marginal portions of the top face of each of the sheets 1, and preferably all of the marginal portions, namely, the side marginal portions 3—3 and the front and rear end marginal portions 4 and 5 respectively of the top face, are free from abrasive, these marginal portions 3—3, 4, and 5 being smooth.

The marginal portions of each of the sheets 1 are formed with a plurality of spaced openings 6 disposed inside of the extreme edges of the sheets, the openings of the respective sheets being arranged to register with openings in the other sheets so as to provide a plurality of spaced composite openings extending through the entire pad inside the edges of the sheets. These composite openings are filled

with glue or similar adhesive material which extends through the openings and engages the base. The adhesive is then permitted to harden, forming columns 7 which serve to connect the sheets together securely over zones or areas greater transversely than the mere thickness of a sheet, so that the individual sheets are not susceptible to becoming removed accidentally, as is the case where the adhesive material is applied only along the extreme edges of the sheets comprising the pad. The marginal portions of the top faces of the sheets, being smooth and free from abrasive, do not collect powdered graphite,

90

and soiling of the user's hands is eliminated to a considerable extent.

In accordance with a further feature of the invention, I provide tabs 8 for facilitating removal of the individual sheets without the user's soiling his hands, these tabs in the form shown comprising extensions on the sheets projecting beyond the rear marginal portions 5 thereof.

10 In the modification shown in Figures 4 and 5, the device comprises a base A' and a pad B' consisting of sheets 1' the central portions of which are provided with abrasive 2' and the side margins 3'-3' and front and rear 15 margins 4'-5' respectively of which are smooth, as in the form shown in Figure 1. However, in the modification, the sheets are not provided with openings as in the Figure 1 construction, but instead the adjacent sheets 20 are joined by means of adhesive applied in spots 7' of greater transverse area than the mere thickness of a sheet between the smooth marginal top face portions of each sheet and the bottom face of the sheet next above. This 25 thickness of the adhesive spots 7' shown in Figure 5 is somewhat exaggerated in order more clearly to illustrate the disposition of the sheets and abrasive spots, it being understood that in practice the spots are much thinner and the sheets lie closely one above the other. The modified form shown in Figures 30 4 and 5 is also provided with tabs 8' to facilitate intentional removal of the sheets, and these tabs, taken in connection with the 35 smooth marginal top face portions of the sheets, contribute to the elimination of soiling of the user's hands. The adhesive spots 7', being disposed between face portions of the adjacent sheets, are in contact with a substantial 40 area of the sheets and serve to secure the latter together much more efficiently than is the case where the adhesive is applied to the edges of the sheets, as in prior devices of this character.

45 To recapitulate the advantages resulting from my invention, the individual sheets may be removed without the aid of a knife and without the user soiling his hands, since the smooth marginal portions of the sheets 50 prevent accumulation of powdered graphite near the edges thereof, and since the tabs are readily accessible. The hazard of individual sheets being separated or of the pads being separated from the base, especially when the 55 device is suspended on a string and susceptible to being bumped against a drafting board or the like, is eliminated because of the more efficient securing of the pads to each other and to the base.

60 Although the devices disclosed herein are considered practical embodiments of the invention, it will be understood that various changes may be made without departing from the spirit of the invention as defined in the 65 claims.

I claim:

1. A device of the character described comprising a plurality of superposed sheets flat throughout their extents and each having a portion provided with abrasive material and a marginal face portion free from abrasive, and adhesive material on said marginal face portions and adjacent portions of the sheets in relatively wide zones for securing together said marginal portions of adjacent sheets.

2. A device of the character described comprising a plurality of superposed sheets flat throughout their extents and each having a portion provided with abrasive material and a marginal face portion free from abrasive, a plurality of registering openings in the said marginal portions of the respective sheets wider than the thickness of the respective sheets, and adhesive material filling said 85 openings.

3. A device of the character described comprising a base, a plurality of superposed sheets flat throughout their extents and mounted on said base and each having the central portion of its top face provided with abrasive material and having marginal portions of its top face free from abrasive, a plurality of spaced relatively large registering openings in the marginal portions of the sheets, and solid columns of material extending through said openings and engaging said sheets and base.

4. A device of the character described comprising a base, a plurality of superposed sheets flat throughout their extents and mounted on said base and each having the central portion of its top face provided with abrasive material and having marginal portions of its top face free from abrasive, a plurality of spaced registering openings in the marginal portions of the sheets wider than the thickness of the respective sheets, columns of adhesive material extending through said openings and engaging said base, and tabs for facilitating removal of individual sheets comprising extensions on said sheets beyond one of the margins of each.

5. A device of the character described comprising a plurality of superposed sheets flat throughout their extents and each having a portion provided with abrasive material and a marginal face portion free from abrasive, adhesive material for securing together 110 said marginal portions of adjacent sheets in relatively wide zones, and a tab integral with each sheet and extending beyond a secured marginal edge thereof.

6. A device of the character described comprising a base, a plurality of superposed sheets flat throughout their extents and mounted on said base and each having the central portion of its top face provided with abrasive material and having marginal por- 130

tions of its top face free from abrasive, and adhesive material interposed in relatively wide zones between and securing together said marginal top face portion of each sheet
5 and the bottom face of the sheet next above.

7. A device of the character described comprising a plurality of superposed sheets, each sheet having a portion provided with abrasive material and a marginal face portion free from abrasive material, and adhesive material on said marginal face portions in spaced apart bodies of relatively large girth securing the sheets together.

10 In testimony whereof, I have hereunto
15 subscribed my name.

CLARENCE A. SMITH, II.
